UNITED STATES PATENT OFFICE

PAUL STERN, OF HUCKINGEN-ON-THE-RHINE, GERMANY

REINFORCING STRUCTURE FOR BLAST-FURNACE CASINGS

Application filed January 9, 1929, Serial No. 331,256, and in Germany October 10, 1927.

This invention relates to reenforcing structures for blast furnace casings.

With the casings of blast furnaces, particularly smelting furnaces, outward bulges occur on more or less large surfaces, the avoidance of which is greatly to be desired. It has hitherto been difficult to repair portions of the casing because the safety of the casing is jeopardized thereby. In the forms hitherto used, not only the specific weight of the smelting furnace casing lying thereover but also the load of the furnace mouth cover, the scaffolding and the cooling chamber exerted a disadvantageous effect.

These disadvantages are overcome according to the invention by a special form of reinforced structure for the casing.

Up to the present, upright supports have been known which are intended to contribute to an increase in the vertical reenforcing of the casing. They are employed simultaneously as ties for the flat iron ring members horizontally surrounding the casing. This arrangement has however, not been found satisfactory as a vertical support and a consequent increase in the stability of the furnace columns has not been attained. Moreover, the weak construction, consequent upon this arrangement, does not allow of any relief to the auxiliary arrangements.

According to this invention, instead of the flat iron ring members, closed ring-shaped plate or grid structures are arranged around strong vertical supports and a portion thereof is so shaped that they can be employed as scaffolding. These structures take any additional loads and transmit them to the vertical supports. In this manner a complete stability of the blast furnace is attained. Deformations in the furnace casings are, moreover, prevented by a metal cover surrounding it.

In order that the invention may be fully understood, I will now describe it by reference to the accompanying drawing, in which:

Figure 1 is an elevation of apparatus constructed in accordance with the invention.

Figure 2 is a horizontal section on the line 50 A—B, Figure 1.

Figures 3 and 4 are sections respectively on the lines C—D Figure 2 and E—F, Figure 3.

Around the furnace casing *d* are placed vertical supports *a* and around these are arranged horizontal ring-shaped structures *b* and *c*. 55

The ring-shaped members *b* preferably form only tension bands whilst the ring-shaped members *c* are suitably made as plate or framework carriers which can be at the same time used as scaffolding for working on the furnace casing and also for supporting the cool water channels. 60

The upper ring-shaped member can also be used as a carrier for the furnace mouth covers. The supports *a* are connected at equal distances to the said ring-shaped structure members *b* and *c*. 65

I claim:

In a stack furnace, the combination of a 70 conical casing, supporting means for said casing, said means comprising a plurality of unitary disconnected substantially vertical supports spaced around the periphery of the casing and extending throughout the vertical 75 extent thereof, a plurality of bands surrounding said vertical members and a plurality of horizontal unitary ring-shaped members surrounding said vertical supports and adapted to coact as framework carriers 80 and scaffolding, said rings and bands pressing the vertical supports against said casing. 85

In testimony whereof I have signed my name to this specification.

PAUL STERN. 85
